HANDLE CONSTRUCTION

Howard Kidd, Cincinnati, Ohio

Application January 4, 1946, Serial No. 638,969

9 Claims. (Cl. 224—45)

1

This invention relates to a handle construction, and is concerned particularly with a foldable type of wire handle that may be applied with advantage to carriers for bottled goods, such as beverages and the like.

An object of the invention is to provide a bottle carrier with an improved type of handle construction which is simple, inexpensive, and convenient to manipulate in conditioning the carrier for use, for stacking, or for storage and shipment.

Another object is to provide an improved handle construction for a carrying device, which incorporates a normally flexible arrangement of links and means cooperating therewith to automatically impart rigidity to the handle structure when lifted and disposed to the operative use position.

A further object is to provide a normally flexible handle structure of the character referred to, which folds flatly onto the body portion of a bottle carrier and about the bottle receptive openings thereof, so as not to interfere with insertion and removal of bottles, and which handle structure when released, falls automatically to a definite position of inoperativeness regardless of the presence or absence of bottles within the carrier.

The foregoing and other objects are attained by the means described herein and illustrated in the accompanying drawings, in which:

Fig. 1 is a perspective view of a bottle carrier, partly broken away, incorporating the improved handle construction of the invention and showing same in the extended or operative use position.

Fig. 2 is an end view of the carrier, on a reduced scale, showing the handle structure in the folded or inoperative position.

Fig. 3 is a top plan view showing the handle structure in the Fig. 2 position.

Fig. 4 is a side elevational view showing the handle structure in the operative use condition.

Fig. 5 is an elevational view of the handle structure as seen on line 5—5 of Fig. 4.

Bottle carriers of the type herein disclosed, are designed for use by purchasers of bottled goods at retail. Such carriers should possess certain characteristics and features of advantage to the storekeeper, the deliveryman, and the promoter of the bottled product, as well as to the purchaser. For example, the carriers should be easily handled in shipment, and for the benefit of the deliveryman, the warehouseman, and the storekeeper, they should lend themselves to ver-

2

tical stacking in a minimum of space when filled with bottles. When empty, the carriers should be even more compact so as to occupy little storage or shipping space.

From the standpoint of the producer or promoter of the bottled goods, it is desirable that the carriers be so constructed as to advertise the goods to the best possible advantage, and they should be practicable, durable, and attractive in appearance. The element of expense of fabrication, of course, also constitutes a factor of interest as it determines to some extent the cost of distribution and the ultimate profit realized incident to sales of the product. Accordingly, it is desirable that the carriers be designed and constructed for rapid production at low cost.

The foregoing considerations, as well as others to be hereinafter mentioned, have determined to a substantial degree the characteristics of the improved bottle carrier now to be described in detail, with reference to the accompanying drawings.

The carrier comprises a horizontal top sheet member or deck 6 having opposite sides 7 and opposite ends 8, with two rows of bottle receptive openings 9 and 10 extending from end to end of the carrier. The rows of apertures are spaced apart, so that between the rows there will be provided a solid area 12 extending lengthwise, said area being adapted to support a hollow hand grip element 13 in the form of an elongated sleeve, which forms part of the carrying handle of the device. The hand grip element, as will be explained, rests upon the outer or upper surface of the top sheet member 6, only when the handle structure is folded or collapsed to the inoperative position, as illustrated by Fig. 2. The bottoms of bottles whose shoulders or bodies are supported by the walls of the bottle openings of the longitudinal rows 9 and 10, are normally supported by means of a bottom tray 14 which is hung from the ends of the top sheet member, preferably by means of hanger arms 15. The hanger arms may be integral with the bottom tray, if desired, and the upper ends of said arms may be welded or otherwise fixedly secured to the inside of a depending flange 16 formed at the ends of the top member, the securing means being indicated at 17. The entire suspension element comprising the tray 14 and the hanger arms 15, may be formed from a single sheet of metal or the like, and will preferably include side flanges 18 turned upwardly at the longitudinal side edges of the tray, these flanges serving to reinforce the tray member, enhance the appearance of the carrier,

and at the same time prevent lateral shifting movement of the bottles resting upon the tray. In order that the tray may have no tendency to sag under the weight of the bottles, a brace member including vertical arms 19-19 may be welded or otherwise fixedly secured to the bottom tray at the locations 20-20, and to the top sheet member at one or more locations such as 21. The brace member preferably is located centrally of and along a horizontal line which bisects the top sheet member from end to end. By so disposing the brace, it is prevented from interfering with the insertion and removal of bottles through the openings provided in the top sheet member. It may here be noted that the rows of bottle receptive openings 9 and 10 may comprise any desired number of openings although for purposes of illustration twelve such openings are indicated. It should be understood, further, that if the carrier be designed to accommodate articles other than bottles, the provision of rows of openings 9 and 10 may be unnecessary, or the top sheet member may in that event be furnished with a single large opening, provided that sufficient metal remains for attachment of the handle structure to the carrier in the manner to be explained hereinafter.

In the preferred form of the device, the top sheet member 6 is provided with a circumferential depending narrow flange 22, end portions of which are indicated at 16. Intermediate the ends of the carrier, the side flanges 22 may be enlarged so as to furnish depending aprons or display panels 23, to which may be applied any suitable advertising material or identifying indicia, relating preferably to the commodity supported within the carrier. The aprons preferably are formed integrally with the top sheet member 6 and its side flanges 22, and will be spaced apart in substantial parallelism at a distance corresponding to the width of the top sheet member. As illustrated by Fig. 2, the aprons or display panels are spaced apart a distance greater than the width of the bottom tray 14, although it is possible, of course, to increase the width of the bottom tray to the approximate width of the top sheet member, should such a construction be considered necessary or desirable.

The handle structure to be applied to the carrier as herein illustrated, comprises a pair of upright U-frames having spaced parallel arms 24 and 25. These arms extend slidably upwardly through pairs of handle guide apertures 26-26 and 27-27, formed in the material of the top sheet member marginally of its opposite sides. The arms 24 and 25 are provided at their lower ends with stops or abutments underlying the top sheet member, to preclude bodily withdrawal of the arms upwardly through the pairs of guide apertures. Such stops or abutments conveniently may be in the form of connecting members 28 and 29, formed integrally with and spanning the upright arms 24 and 25. It will be appreciated, of course, that arms 24 and 25 need not be connected together at their lower ends, although the lower ends will necessarily include stops or abutments for the purpose above explained. In the simplest construction, however, it is considered preferable to provide the arms 24 and 25 as integral parts of an upright U-frame as shown.

The remainder of the handle structure comprises the hollow hand grasp or sleeve 13, and the inverted U-frames 49 and 50 associated therewith. Each of the frames 49 and 50 comprises a pair of substantially parallel arms 31 and 32 joined at their inner ends by means of

5 a connecting member 33 which preferably is integral with the arms 31 and 32. Connecting members 33 maintain a spaced relationship with the arms corresponding with the distance between the arms 24 and 25 of the upright U-frames, as indicated upon Fig. 3.

10 The arms of the inverted U-frames 49 and 50 have terminal ends 34 and 35 adapted to pivotal connection with the terminal ends 36 and 37 of the upright U-frames, the pivotal connections being conveniently effected by shaping the terminal ends of the arms as eyes to be interlocked as shown. The eyes formed by the terminal ends 34 and 35 of the inverted U-frames, will preferably rest in vertical planes traversing the width of the carrier, whereas the eyes formed by the terminal ends 36 and 37 of the upright U-frames rest in vertical planes extending lengthwise of the carrier.

15 20 By reason of the hinge eye connections referred to, the opposed upright U-frames 24-25 and 27-27, may be elevated in the guide apertures 26-26 and 27-27, by grasping and lifting the hand grip 13 and its associated inverted U-frames 49 and 50, until the stops or connecting members 28 and 29 contact the inner or undersurface of the top sheet member. Conversely, a lowering movement of the hand grasp 13 and its associated frames 49 and 50, permits the arms 24 and 25 25 of the upright U-frames to lower within the pairs 30 of guide apertures, as illustrated upon Fig. 2, so that the frames last mentioned will depend vertically alongside the aprons or display panels 23-23. In this condition of the handle structure, the inverted U-frames 49 and 50, as well as the hand grip 13, rest upon or in close proximity with the outer or upper surface of the top sheet members 6. To achieve this result, the arms of frames 49 and 50 must be no longer than 40 half the width of the top sheet member.

35 To ensure the maximum degree of compactness of the assembly when the handle structure is folded or collapsed to the Fig. 2 condition, the pairs of guide apertures are made T-shaped, of 45 configuration, with the caps or heads of the T extending lengthwise of the carrier, and the legs 38 thereof extending transversely and inwardly from the side edges of the top sheet member. This form of guide aperture permits partial entry 50 of the terminal end eyes 36 and 37 through the top sheet member at the heads of the T, and partial entry of the terminal eyes 34 and 35 at the leg of each T. As will be understood, a guide aperture of each pair is disposed directly opposite 55 a guide member of the other pair of apertures, so that the handle structure will be properly centered relative to the top sheet member of the carrier.

60 When the handle structure is lowered to the folded or collapsed condition of Figs. 2 and 3, no part thereof will interfere with the insertion and removal of bottles through the bottle receptive openings of the rows 9 and 10, and moreover, the handle structure in that condition is lowered to an elevation well below the tops of all bottles projecting upwardly through the openings, so that a multiplicity of carriers filled with bottles may be stacked vertically to provide an attractive display requiring a minimum of floor space. As illustrated by Fig. 3, the hand grasp member or sleeve 13 rests upon the top of the carrier, along the central area between the rows of openings, while the arms of the inverted U-frames 49 and 50 extend between adjacent bottles of each

row. This relationship of the parts is illustrated by Fig. 2, as well as by Fig. 3.

When the hand grip 13 is grasped and elevated vertically, it lifts the several frames to the positions illustrated by Figs. 1 and 4, at which the stop or abutment members 28 and 29 contact the undersurface of top sheet member 6, thereby making it possible to transport the carrier by means of the handle structure. In this operative or extended position of the parts, the hand grip member 13 is elevated above the tops of all bottles placed within the carrier, so that the unit may be transported with the greatest ease and convenience.

To enhance the effectiveness of the handle structure, so that it may readily be disposed to either the operative or the inoperative position, and to impart a limited amount of rigidity and substantiality when the handle structure is extended to the operative position, the hand grip or elongated sleeve 13 is furnished at its opposite ends with the extending lugs or separators indicated at 40 and 41. These lugs or separators extend outwardly between the adjacent arms of the inverted U-frames, so that the arms may not swing downwardly and inwardly toward one another, except to a limited extent as permitted by the lugs or separators. This condition of the frames 49 and 50 is illustrated by Fig. 5, wherein it will be apparent that lifting of the hand grip 13 will not permit further lowering of the frames 49 and 50 toward one another. The rigidity thereby established between the frames and the hand grip which embraces their connecting members 33, imparts a desired carrying stability to the handle structure, which facilitates transportation of the carrier. It will be noted further, by referring to Fig. 5, that by releasing the hand grip 13, the arms 24-24 of the upright U-frames will be properly suspended for immediate gravitation through the guide apertures at opposite sides of the top sheet member. If it were not for the separating function of the lugs 40 and 41, the arms 24 would not be properly poised for immediate slidability downwardly through the guide apertures. As previously stated, in the operative or extended condition of the handle parts illustrated by Fig. 5, the hand grip member 13 is disposed slightly above the tops of all bottles supported within the carrier.

The carrier herein disclosed may be manufactured inexpensively at a rapid production rate, using common sheet metal and wire stock. It is constructed to withstand hard usage and abuse, and will readily be found superior in many respects to carriers heretofore constructed of cardboard, wood, and other types of materials. The carrier may be modified in various ways as to minor details of construction, within the scope of the appended claims, without departing from the spirit of the invention.

What is claimed is:

1. In combination, a carrier including a horizontal top sheet member having outer and inner surfaces with opposed marginal portions pierced to provide two pairs of handle guide apertures spaced apart, an articulated handle including a pair of upright U-frames and a pair of inverted U-frames, each of said U-frames comprising an intermediate connecting member and a pair of arms extending substantially in a common direction laterally from the ends of the connecting member, said arms each having a terminal end, the arms of each upright U-frame being slidably extended upwardly through one pair of

guide apertures at one side of the top sheet member, with the intermediate connecting member of each upright frame underlying the top sheet member, means pivoting the terminal ends of each inverted U-frame arm to the terminal ends of an upright U-frame arm, and a hollow hand grip in the form of an elongated sleeve embracing the connecting members of both inverted U-frames.

2. In combination, a carrier including a horizontal top sheet member having outer and inner surfaces with opposed marginal portions pierced to provide two pairs of handle guide apertures spaced apart, an articulated handle including a pair of upright U-frames and a pair of inverted U-frames, each of said U-frames comprising an intermediate connecting member and a pair of arms extending substantially in a common direction laterally from the ends of the connecting member, said arms each having a terminal end, the arms of each upright U-frame being slidably extended upwardly through one pair of guide apertures at one side of the top sheet member, with the intermediate connecting member of each upright frame underlying the top sheet member, means pivoting the terminal ends of each inverted U-frame arm to the terminal ends of an upright U-frame arm, and a hollow hand grip in the form of an elongated sleeve embracing the connecting members of both inverted U-frames, said sleeve including end lugs interposed between and separating the adjacent arms of the inverted U-frames, to limit and stop movement of the latter toward parallelism with one another.

3. In combination, a carrier including a horizontal top sheet member having outer and inner surfaces with opposed marginal portions pierced to provide two pairs of handle guide apertures spaced apart, an articulated handle including a pair of upright U-frames and a pair of inverted U-frames, each of said U-frames comprising an intermediate connecting member and a pair of arms extending substantially in a common direction laterally from the ends of the connecting member, said arms each having a terminal end, the arms of each upright U-frame being slidably extended upwardly through one pair of guide apertures at one side of the top sheet member, with the intermediate connecting member of each upright frame underlying the top sheet member, means pivoting the terminal ends of each inverted U-frame arm to the terminal ends of an upright U-frame arm, and a hollow hand grip in the form of an elongated sleeve embracing the connecting members of both inverted U-frames, said sleeve including end lugs interposed between and separating the adjacent arms of the inverted U-frames, to limit and stop movement of the latter toward parallelism with one another, the distance from each handle pivot means to the sleeve being approximately half the distance across the top sheet member between the pairs of guide apertures.

4. In combination, a carrier including a horizontal top sheet member having outer and inner surfaces with opposed marginal portions pierced to provide two pairs of handle guide apertures spaced apart, an articulated handle including a pair of upright U-frames and a pair of inverted U-frames, each of such U-frames comprising an intermediate connecting member and a pair of arms extending substantially in a common direction laterally from the ends of the connecting member, said arms each having a terminal end, the arms of each upright U-frame being slidably

extended upwardly through one pair of guide apertures at one side of the top sheet member, with the intermediate connecting member of each upright frame underlying the top sheet member, means pivoting the terminal ends of each inverted U-frame arm to the terminal ends of an upright U-frame arm, and a hollow hand grip in the form of an elongated sleeve embracing the connecting members of both inverted U-frames, said sleeve including end lugs interposed between and separating the adjacent arms of the inverted U-frames, to limit and stop movement of the latter toward parallelism with one another, the distance from each handle pivot means to the sleeve being approximately half the distance across the top sheet member between the pairs of guide apertures, two rows of bottle supporting means associated with the top sheet member spaced between the guide apertures, and a central supporting area between the rows to support the sleeve when lowered into the top sheet member, said supporting area being at least as wide as the diameter of the sleeve.

5. In combination, a carrier including a horizontal top sheet member having outer and inner surfaces with opposed marginal portions pierced to provide two pairs of handle guide apertures spaced apart, an articulated handle including a pair of inverted U-frames each consisting of a pair of arms having terminal ends and an intermediate connecting member for the arms, a hand grasp in the form of an elongated sleeve embracing loosely therein the intermediate connecting member of both U-frames, other arms pivoted to and depending from the terminal ends of the inverted U-frames, said other arms each extending slidably through a handle guide aperture of the top sheet member, stop means on said other arms beneath the top sheet member to preclude upward withdrawal of said other arms from the guide apertures, and means on the sleeve to maintain a separated condition of the inverted U-frame arms, so that said frames may not closely approach parallelism with one another as the sleeve is lifted to an elevation above the top sheet member.

6. In combination, a carrier including a horizontal top sheet member having outer and inner surfaces with opposed marginal portions pierced to provide two pairs of handle guide apertures spaced apart, an articulated handle including a pair of inverted U-frames each consisting of a pair of arms having terminal ends and an intermediate connecting member for the arms, a hand grasp in the form of an elongated sleeve embracing loosely therein the intermediate connecting member of both U-frames, other arms pivoted to and depending from the terminal ends of the inverted U-frames, said other arms each extending slidably through a handle guide aperture of the top sheet member to preclude upward withdrawal of said other arms from the guide apertures, and means on the sleeve to maintain a separated condition of the inverted U-frame arms, so that said frames may not closely approach parallelism with one another as the sleeve is lifted to an elevation above the top sheet member, the length of each U-frame arm being no greater than half the distance between two opposed handle guide apertures.

7. In combination, a carrier body having opposed handle guides located at opposite sides of the body, an articulated handle including a pair of inverted U-frames each consisting of a pair of arms having terminal ends and an intermediate connecting member for the arms, a hand grasp in the form of an elongated sleeve embracing loosely therein the intermediate connecting member of both U-frames, other arms pivoted to and depending from the terminal ends of the inverted U-frames, said other arms each extending slidably through a handle guide aperture of the top sheet member to preclude upward withdrawal of said other arms from the guide apertures, and means on the sleeve to maintain a separated condition of the inverted U-frame arms, so that said frames may not closely approach parallelism with one another as the sleeve is lifted to an elevation above the top sheet member.

diate connecting member for the arms, a hand grasp element embracing loosely the intermediate connecting members of the U-frames, other arms pivoted to and depending from the terminal ends of the inverted U-frames, said other arms each extending slidably through the handle guides of the carrier body, stop means on said other arms to preclude withdrawal and separation of said other arms from the handle guides as the last mentioned arms slide therein in one direction, and means on the hand grasp element to maintain a separated condition of the inverted U-frame arms, so that said frames may not closely approach parallelism with one another as the hand grasp element is lifted bodily to an elevation above the carrier body.

8. In combination, a carrier body having opposed handle guides located at opposite sides of the body, an articulated handle including a pair of inverted U-frames each consisting of a pair of arms having terminal ends and an intermediate connecting member for the arms, a hand grasp element embracing loosely the intermediate connecting members of the U-frames, other arms pivoted to and depending from the terminal ends of the inverted U-frames, said other arms each extending slidably through the handle guides of the carrier body, stop means on said other arms to preclude withdrawal and separation of said other arms from the handle guides as the last mentioned arms slide therein in one direction, and means on the hand grasp element to maintain a separated condition of the inverted U-frame arms, so that said frames may not closely approach parallelism with one another as the hand grasp element is lifted bodily to an elevation above the carrier body.

9. In combination, a carrier including a horizontal top sheet member having outer and inner surfaces with opposed marginal portions pierced to provide two pairs of handle guide apertures spaced apart, an articulated handle including a pair of inverted U-frames each consisting of a pair of arms having terminal ends and an intermediate connecting member for the arms, a hand grasp element embracing the intermediate connecting member of both U-frames, other arms pivoted to and depending from the terminal ends of the inverted U-frames, said other arms each extending slidably through a handle guide aperture of the top sheet member, stop means on said other arms beneath the top sheet member to preclude upward withdrawal of said other arms from the guide apertures, and means on the hand grasp element to maintain a separated condition of the inverted U-frame arms, so that said frames may not closely approach parallelism with one another as the hand grasp element is lifted to an elevation above the top sheet member.

HOWARD KIDD.
